UNITED STATES PATENT OFFICE

VICTOR A. MARES, OF NEW YORK, N. Y.

VENTILATOR

Application filed December 24, 1927. Serial No. 242,393.

My invention relates to devices which are readily applicable to ordinary window frames to control "draft", or ventilation of the room.

5 An important object is to provide such devices of simple and economical form, and which may, therefore, be sold at low price to householders or others, for ready installation by them, and easily removed, without 10 injury to the window structure.

A further object is to provide improved structural and operative features in ventilating appliances of this class, regardless of cost.

15 To realize the stated and other objects, the invention consists, as embodied in one representative form, of generally-triangular end members or plates having formations readily applicable in the sash-channels of the window frame, and other, diagonal formations to receive retaining or clamping members in which the wind baffling or draft regulating device is inserted, such device consisting of wire screening or textile fabric in a suitable 20 adjustable or non-adjustable frame, or an imperforate sheet of suitable material such as glass or fibre, cardboard, etc., of suitable character. The opposite end members and the aforesaid diagonal formations are related to 25 one another to locate the bottom edge portion of the baffle exteriorly of and preferably in contact with the outer edge of the inner sill, and within the usual recess in the window frame forwardly of the inner sill.

30 Preferably each end piece is formed from a blank of flat sheet metal, cut to proper shape and pressed or bent to final form, and the clamping or retaining devices insertable in the diagonally arranged channel formations 35 of the end plates are also desirably of pressed sheet metal.

The characteristics and advantages of the invention are further sufficiently explained in connection with the following detail description of the accompanying drawings, which illustrate representative embodiments. After considering these examples, skilled persons will understand that many variations may be made without departing from 45 the principles involved, and we contemplate 50

the employment of any structures that are properly within the scope of the appended claims.

Fig. 1 is an inside front elevation of a 55 ventilating structure embodying the invention in one form, applied to a window.

Fig. 2 is a section at 2—2, Fig. 1.

Fig. 3 is a section at 3—3, Fig. 1.

Fig. 4 is a side elevation of one of the end members. 60

Fig. 5 is a perspective view of one of the holding clamping channels strips.

Fig. 6 is a view of a blank from which an end member is formed. 65

Fig. 7 is a fragmentary elevation showing 65 a different type of shield or baffle, in position.

Fig. 8 is a perspective view of a modified form of end member.

Fig. 9 is a top plan of the same, in operative 70 position.

Referring first to the embodiment shown in Figs. 1 to 6: Fig. 6 shows a blank B properly shaped for bending to produce one of the end members E of Fig. 4. The blank 75 includes a generally triangular portion or plate 1 having a top edge 2, a vertical side edge and a diagonal side edge 4, the last named edge being jointed at the apex 5 of the triangular plate portion. The portions of 80 the integral blank are shown by dotted lines which indicate fold or bending lines. Strips 6 and 7 are arranged consecutively beyond the diagonal edge 4, being the same length as that edge. Next to strip 7 is a strip 8 85 having a diagonal lower edge 9. Successively next to strip 8 are strips 10 and 11 of lengths equal to the greatest length of strip 8. Connected successively to the vertical edge 90 3 are strips 12, 13.

Strip 11 has end flaps 14 and 15. Strip 8 has an end flap 16. Strip 12 has an inner side flap 17. Plate portion 1 has a top flap 18 along its edge 2. Strip 13 has at its upper end a fastening prong 19. 95

The blank is folded by any suitable method or mechanism to the form shown in Figs. 3 and 4, where it will be observed that the strips 12 and 13 are bent to produce a formation of L shape fitting in the sash channel C 100

of the window frame F. Strips 6 and 7 are folded together to form a flange 20 and strips 10 and 11 are folded together to form a flange 21, these flanges being connected by strip 8 which remains parallel with plate portion 1. The described strip formations or flanges produce a channel having convergent walls. The various flaps are folded over to secure the respective parts together as is sufficiently evident in Fig. 4 by comparison with Fig. 1. The margin of strip adjacent edge 9 is brought over the flap 17 of strip 12 and these portions are secured together by welding, soldering or otherwise. The end piece is put in position as best shown in Figs. 1, 2, and 3, with its lower end resting on the window sill S and with the L formation 12, 13 located as above stated, and is secured by driving the point or prong 19 into the side frame member, this prong being bent at a right angle to the strip 19.

Any suitable window screen or baffle may be inserted in the diagonal channels of the end members. It is preferred, however, to provide channel strips or clamping strips 30, Fig. 5 which are bent up from a flat sheet metal including a base strip 31, side strips 32 slightly convergent, and end strips 33 which are turned inwardly. A clamping strip is applied to each end of any suitable screen or baffle such as K, Fig. 1, this being a window screen of the collapsible type including a frame supporting wire mesh or other fabric. The clamping strips are placed about the end frame members and the free ends of strips 32 are then yieldably bendable to engage the strips 33 within the inward edges of the frame members. The baffle strips with the frame in place are then pushed down into the upper ends of the diagonal channel formations of the end members until the baffle is located as shown in Fig. 1 and 2, and particularly to locate the lower edge portion of the baffle K within the usual recess in the window-frame forwardly of the inner sill S, in a position to divert upwardly air entering below the raised lower sash LS. As appears in Fig. 2, by the projection of the baffle with its lower edge portion in advance of the inner sill S of the window, and particularly rain and dust, subject to the force of wind, is prevented from entering within the window opening under the baffle.

Instead of a baffle or screen of the type described a sheet of any suitable imperforate material may be inserted in the clamping strips 32 and by their agency retained in the end members. For example, heavy paper or cardboard may be employed for this purpose and when so used the clamping flanges 33 will properly engage the opposite faces of the baffle sheet and will properly adapt themselves to its thickness and properly hold the baffle in position in the end members. Fig. 7 shows such a solid baffle sheet or board W

in operative position. Baffles of this character may be supplied with any suitable flat or embossed surface decorations such as D, to add to the decorative appearance of the room in which the appliances are used. Such solid baffles are wind-proof, and completely deflect the entering air, and they may also be water-proof or treated on the outer face with any suitable water-proofing material, to render them impervious to entering moisture, and at the same time prevent moisture being blown into the room.

Figs. 8 and 9 show a modification, principally in the sheet metal end member E¹. This consists of a central portion or triangular plate 1^a similar to the previous example, provided at its inner edge with integral, angularly-bent strips 12, 13 producing an L-shaped formation to fit in the sash channel, also as in the previous example. At its outer, diagonal edge the plate has a single integral strip or flange 40 bent at a right angle and having an overturned and pressed margin 41 to provide a smooth, rounded edge 42. To co-operate with this flange the plate is provided with flexible or resilient clips 44 consisting of pieces of the plate material punched out and bent to the positions shown, substantially parallel to flange 40. The clips 44 in co-operation with the flange provide a channel in which the baffle board such as W of Fig. 7 or the screen K of Fig. 1 may be inserted directly, or by means of clamping strips such as 32 of Fig. 5.

The end members may be secured in position in any suitable way, such as shown in the previous example. Preferably, however, securing devices are provided in the form of prongs 48 punched out of the material of the strip 12, and bent to the positions shown best in Fig. 9, that is, substantially parallel to and spaced from the plate 1^a, and these prongs are driven into the inner face of the strip or cleat 50 which forms the inner margin of the sash channel, and is secured to the facing 51 of the window frame. In addition, a blade or finger 52 may be provided, punched out of the material of flange 12, and bent parallel to flange 13, this finger being forced or driven into the space or joint between strip 50 and the window frame member 51, in a manner clearly explained in Fig. 9.

I claim:

1. In a ventilating appliance for a window frame provided with an inner sill having its exterior edge disposed adjacent to and interiorly relative to the sash channel, an end structure of pressed sheet metal comprising a triangular plate portion, a formation at the vertical edge thereof adapted for insertion in the sash channel of a window frame, and a channel formation at the diagonal edge of the plate portion, said chan-

nel formation being adapted to slidably receive a clamping member in which ends of an air baffle are inserted, said formation insertable in said sash channel being substantially of L section, the lower end of said channel formation terminating in the same vertical plane as the outer edge of said sill.

2. In a ventilating appliance for a window frame provided with an inner sill having its exterior edge disposed adjacent to and interiorly relative to the sash channel, an end structure of pressed sheet metal comprising a triangular plate portion, a formation at the vertical edge thereof adapted for insertion in the sash channel of a window frame, and a channel formation at the diagonal edge of the plate portion, said channel formation being adapted to slidably receive a clamping member in which ends of an air baffle are inserted, said formation insertable in said sash channel being substantially of L section, and means on a part of said formation for securing it to the window frame, the lower end of said channel formation terminating in the same vertical plane as the outer edge of said sill.

3. In a ventilating appliance, an end structure of pressed sheet metal comprising a triangular plate portion, a formation at the vertical edge thereof adapted for insertion in the sash channel of a window frame, and a channel formation at the diagonal edge of the plate portion, said channel formation being adapted to slidably receive a clamping member in which ends of an air baffle are inserted, a lower portion of said channel formation having a diagonally-cut margin overlapping a flap on a lower portion of the formation which is located in the sash channel, for securing said portions together.

In testimony whereof I have signed this specification this 8th day of Dec., 1927.

VICTOR A. MARES.
